UNITED STATES PATENT OFFICE.

SIMON JAFFE, OF MONTREAL, QUEBEC, CANADA.

DESIGN FOR A MEMORANDUM STAND.

• 61,163.

Specification for Design.

Patented July 4, 1922.

Application filed November 28, 1921. Serial No. 518,455. Term of patent 7 years.

To all whom it may concern:

Be it known that I, SIMON JAFFE, a citizen of the United States of America, residing at Montreal, in the county of Hochelaga and Province of Quebec, Dominion of Canada, have invented a new, original, and ornamental Design for Memorandum Stands, of which the following is a specification, reference being had to the accompanying drawing, forming part thereof.

In the drawings is shown a perspective view of my new design memorandum stand.

I claim:

The ornamental design for a memorandum stand, as shown.

SIMON JAFFE.
